CLAIM

The ornamental design for control mechanism for a chair, as
shown.

DESCRIPTION

FIG. 1 is a top, front and left side perspective view of control
mechanism for a chair showing our design;

FIG. 2 is a right side elevational view thereof;

FIG. 3 is a left side elevational view thereof;

FIG. 4 is a top plan view thereof; and,

FIG. 5 is a front elevational view thereof.
